UNITED STATES PATENT OFFICE.

BENJAMIN A. MITCHELL, OF ST. GEORGE, NEW YORK.

SCREENING MACHINE AND SCREEN CLOTH THEREFOR.

Application filed May 23, 1919, Serial No. 299,090. Renewed April 26, 1923.

To all whom it may concern:

Be it known that I, BENJAMIN A. MITCHELL, a citizen of the United States, residing at St. George, Staten Island, and State of New York, have invented certain new and useful Improvements in Screening Machines and Screen Cloth Therefor, of which the following is a specification.

This invention relates to an improved form of wire screen cloth adapted for use in vibrating or stationary screens for screening ore, coal, or other materials. The invention is of particular advantage when used in screening machines wherein means are employed for producing tension in the screen cloth, one form of such apparatus being described and claimed in my copending application, Serial No. 258,466, filed October 16, 1918.

In vibrating screens in which the body of the screen cloth is caused to vibrate by the application thereto, by mechanical or other means, of a vibrating force applied in a plane normal to the plane of the screen, it is found that the amplitude of the vibration of the wires composing the screen cloth increases with the tension in the wires and the size and stiffness thereof. This is due to the fact that fine wires which have no inherent stiffness, and cannot be pulled very taut, have a tendency to muffle or damp any vibration imparted to them. Heavier wires, however, both because they may be tensioned higher and because they possess an inherent stiffness, are more active and resilient when set into vibration, and such cloth has a greater capacity for separating or screening the fine particles from the coarse ones.

The principal object of the present invention is to provide a form of screen cloth which possesses the qualities of a screen of fine mesh, while at the same time being capable of greater activity and amplitude of vibration than other screens having a similar mesh or number of openings per square inch. This improvement is effected by embodying in the structure of the screen cloth of fine mesh and formed of fine wire, a number of heavier wires which are spaced apart and extend in the direction in which tension is applied. In this construction the more active vibrations set up in the heavy wires are easily and positively imparted to the intervening parallel fine wires by the other wires of the woven screen which cross at right angles to the said heavy and fine wires.

Other features and advantages of the invention will appear more clearly hereinafter.

The nature of the invention will be understood from the following specification, taken with the accompanying drawings, in which one embodiment is illustrated.

In the drawings—

Figure 1 is a plan view showing the improved screen cloth mounted in a screen frame adapted to produce tension therein;

Fig. 2 shows a side elevation of the apparatus illustrated in Fig. 1;

Fig. 3 is an enlarged sectional view showing the method of connecting the screen cloth to the frame;

Fig. 4 is a side elevation of a screening machine, showing one means for producing vibrations in the tensioned screen;

Fig. 5 is a side elevation of the apparatus illustrated in Fig. 4, showing a part of the vibrator in section;

Fig. 6 illustrates a modified form of the invention in which an oblong mesh is formed in the screen cloth by spacing the wires running in one direction at greater intervals than the wires running at right angles thereto; and

Fig. 7 is a plan view of another modified form of the invention in which the spaced heavy wires run in both directions.

In the drawings the invention is shown as comprising a woven wire screen cloth 10, which is composed of a series of longitudinal wires 11, and a series of transverse wires 12, each series of wires being formed of relatively fine wire. At intervals transversely of the screen cloth heavy longitudinal wires 13 are employed in place of the fine wires 11, so that a number of fine wires are interposed between and lie parallel to each pair of larger wires 13, which are relatively heavy and preferably have considerable inherent stiffness.

In the practical use of the screen cloth, it may be mounted in a screen frame 15 having transverse flanges 16 along the opposite up-turned ends thereof, these flanges being apertured to be engaged by bolts 17 which are adjusted by the nuts 18. The bolts 17 are connected at their inner ends to tubes 19, which are slotted longitudinally on the sides thereof opposite the bolts to receive the screen cloth 10 which is extended around rods 20 within the tubes. Each rod 20 is of greater diameter than the width of the slot, so that when the bolts 17 are adjusted to

separate the tubes 19, the rods 20 cause a snubbing action between the edges of the slots and the interposed portions of the screen cloth, whereby a secure grip is maintained upon the screen cloth regardless of the tension produced therein by the adjustment of the bolts 17 and nuts 18. The heavy wires 13 of the screen cloth extend in the direction in which the tension is applied, so that they operate to render the longitudinal fine wires 11 more active and to maintain a more permanent and uniform vibratory action throughout the area of the screen.

One improved method of producing vibrations in the tensioned screen is illustrated in Figs. 4 and 5, wherein the frame 15 and the screen cloth 10 carried thereby are mounted in inclined positions, so that the material to be screened may be fed to the upper edge thereof and caused to flow down over the tensioned screen. Vibrations are produced in the screen cloth by a rotary vibrator 25, which comprises a casing 26 having inclined rotary elements 27 therein adapted to rotate with the rotation of a shaft 28 driven by a pulley or motor 29. The casing 26 of the motor is connected to the screen cloth by plates 30 which are attached to the ends of the casing, so that the rotary vibrations set up in the casing of the vibrator are imparted to the screen cloth in planes at right angles thereto, thereby setting up vibrations directly in the screen cloth, as described and claimed in my prior application above referred to.

In Fig. 6 of the accompanying drawings, I have shown a modified form of the invention in which the screen cloth 35 is composed of longitudinal strands of fine wire 36 located between longitudinal strands 37 of heavy wire which are spaced apart and adapted to extend in the direction in which tension is applied. The transverse fine wires 38 which are interwoven with the wires 36 and 37 are arranged closer together than the longitudinal wires, so that a mesh of oblong rectangular form is produced. This construction is of advantage since the numerous transverse wires are adapted to impart the vibrations of the longitudinal heavy wires effectively to the longitudinal fine wires.

Fig. 7 shows another modification in which the longitudinal and transverse fine wires 40 and 41 are interwoven with longitudinal and transverse heavy wires 42 and 43, respectively, the heavy wires being spaced apart. The vibrations of one set of heavy wires are effectively imparted to the fine wires through the transverse heavy wires.

This invention is of particular advantage when incorporated in screens of very fine mesh, for example, twenty mesh or finer. The wires in these screen cloths are very delicate, and the vibrating means must impart its vibrations thereto with great gentleness if

imparted directly to the screen cloth, or, as imparted, in general practice in the art of very fine screening, by vibrations set up in the frame holding the screen cloth. The vibrations set up in these fine screen cloths may be fairly active at the points of application, but in ordinary screening machines they are soon damped or smothered by the material being screened, so that a large area of the screen surface is completely deadened and not vibrating. However, with the present improvement screen cloths of fine mesh can be operated satisfactorily and efficiently due to the fact that the heavier wires can be made heavy enough to receive a very heavy blow or vibration of large amplitude, and these heavy wires being suitably spaced tend to distribute the vibrations uniformly throughout the entire area of the screening surface.

It is desirable usually in screening operations to grip the edges of the screen cloth continuously, so that each wire running in the direction of applied tension is securely held to secure uniform tension throughout the screening area and prevent the formation of pockets or depressions in the screening surface. When using the screen of the present invention, however, the heavier wires alone are positively and securely held and are subjected to a heavy tension, and while this arrangement is not adapted to give a uniform tension throughout the entire screening area, it produces a screening surface which is free from depressions or pockets and more active and resilient when under forced vibration than screen cloths previously known to the art.

Although I have shown particular embodiments of the invention and have explained particular applications thereof, it will be understood that the invention may be employed in various forms and uses without departing from the scope of the appended claims.

What I claim is:

1. A woven wire screen cloth adapted to be supported in a state of tension and set into vibration by impact comprising a warp and weft of relatively fine wires, said fine wires being replaced at predetermined intervals with relatively heavy wires arranged to receive initially the stress of vibration.

2. A woven wire screen cloth adapted to be supported in a state of tension from two opposite edges and set into vibration by impact comprising a warp and weft of relatively fine wires, said fine wires extending in the direction of tension being replaced at predetermined intervals with relatively heavy wires arranged to receive initially the stress of vibration.

3. A woven wire screen cloth adapted to be supported in a state of tension from longitudinally spaced apart edges and set into vibration by impact comprising a warp and

weft of relatively fine wires; the longitudinal fine wires being replaced at predetermined intervals with relatively heavy wires which are arranged to receive initially the 5 stress of vibration.

4. In combination, a woven screen cloth having relatively heavy wires extending longitudinally thereof with relatively fine longitudinal wires interposed therebetween, 10 means for producing tension in said screen cloth longitudinally thereof, and means for vibrating said screen cloth.

5. In combination, a woven screen cloth having relatively heavy wires extending 15 longitudinally thereof with relatively fine longitudinal wires interposed therebetween, means for producing tension in said relatively heavy wires, and means for producing vibrations directly in said screen cloth.

20 6. The combination in a screening machine, of an inclined woven wire screen cloth comprising interwoven fine wires and heavy wires extending longitudinally of said screen cloth and interwoven with said

fine wires, means engaging said heavy wires 25 for supporting said screen cloth, means for causing loose materials to pass downwardly over said inclined screen cloth transversely to said heavy wires, and means for imparting vibrations to said heavy wires. 30

7. The combination in a screening machine, of an inclined woven wire screen cloth comprising interwoven fine wires and heavy wires extending longitudinally of 35 said screen cloth and interwoven with said fine wires, means engaging said heavy wires for supporting said screen cloth, means for causing loose materials to pass downwardly over said inclined screen cloth transversely to said heavy wires, and means for imparting 40 circular vibrations to said heavy wires in planes perpendicular thereto and in alignment with the paths of travel of said materials thereover.

In testimony whereof, I have subscribed 45 my name.

BENJAMIN A. MITCHELL.
